UNITED STATES PATENT OFFICE.

WILLIAM PRIESSNITZ BONWICK, OF LONDON, ENGLAND, ASSIGNOR TO HIMSELF, LEON NAPOLEON LOEB, AND MAITLAND LUMLEY, OF SAME PLACE.

BOTTLE-STOPPER.

SPECIFICATION forming part of Letters Patent No. 450,479, dated April 14, 1891.

Application filed June 2, 1890. Serial No. 354,030. (No model.) Patented in England July 20, 1888, No. 10,497, and July 22, 1889, No. 11,674; in Belgium June 6, 1889, No. 86,543, and June 19, 1890, No. 90,967; in Germany June 6, 1889, No. 50,119, and in Victoria July 5, 1889, No. 6,867.

To all whom it may concern:

Be it known that I, WILLIAM PRIESSNITZ BONWICK, a subject of the Queen of Great Britain and Ireland, residing at Blomfield Road, Paddington, London, in the county of Middlesex, England, have invented Improvements in Bottle-Stoppers, (for which I have obtained the following patents: British Patents No. 10,497, dated July 20, 1888, and No. 11,674, dated July 22, 1889; Victorian Patent No. 6,867, dated July 5, 1889; Belgian Patents No. 86,543, dated June 6, 1889, and No. 90,967, dated June 19, 1890, and German Patent No. 50,119, dated June 6, 1889,) of which the following is a specification.

My invention relates to an improved bottle-stopper, consisting of a combination in one of a valve, a button or knob, (hereinafter called a "knob,") a connecting part, (hereinafter called a "stem,") a groove bounded by said valve, knob, and stem, and one or more channels or passages formed partly in the knob and partly in the stem, the arrangement being such when applied to a bottle suitably formed with an internal groove and fitted with one or more elastic rings surrounding the stem of the stopper and charged with aerated liquid that the pressure of gas in the bottle will keep the valve normally against an elastic seat formed by said ring, or by one of them when using more than one; but if the bottle be inverted and the knob be pressed the valve will be caused to leave its seat, liquid will flow out of the bottle by the before-mentioned channels, and if the knob be released the valve will be returned to its seat by the pressure thereon of the gas, thus closing the bottle until the knob is again depressed. This construction enables any desired portion of the contents of the bottle to be withdrawn at pleasure.

When the stopper is applied to a bottle containing fermented liquor, I so construct and arrange the stopper and ring or rings that the stopper will be normally held to its seat by the action of said ring or rings.

When this modified construction of stopper and ring or rings is applied to a bottle containing still liquid, the stopper is constructed with two channels, and to open the bottle

must be moved inward sufficiently far to cause both channels to be uncovered or opened so that the liquid may flow out by one and air enter by the other. The channels or passages may advantageously be formed at opposite sides of the stopper.

Stoppers as described may be formed in one piece of glass.

In the accompanying drawings, Figure 1 is a vertical section of the neck of a bottle fitted with a stopper according to this invention, the stopper being shown closed. Fig. 2 is a similar view to Fig. 1, but showing the bottle-neck inverted and the stopper moved inward to the open position by an opener resting upon the rim of a tumbler, which, as well as the opener, is indicated in dotted lines. Fig. 3 is a plan of the stopper and ring removed from the bottle-neck. Fig. 4 is an elevation of the stopper alone. Figs. 5 and 6 are respectively a vertical section and a plan of a modified form of stopper with elastic ring. Figs. 7 and 8 and Figs. 9 and 10 are similar views to Figs. 5 and 6, respectively, illustrating other modified forms of stopper with elastic ring. Fig. 11 is a vertical section illustrating a modified form of bottle-neck and stopper therefor, and Fig. 12 is an elevation of the stopper alone. Fig. 13 is a similar view to Fig. 11, illustrating a further modification. Fig. 14 is a vertical section showing a bottle-neck provided with a stopper and two elastic rings.

The bottle-stopper shown in Figs. 1 to 4, inclusive, can be made in one piece, of suitable material. Usually I make it of glass, and it comprises a valve 1, a knob 2, a stem 3, and two channels 4, 4, each made partly in said knob and partly in said stem. These channels are parallel to the axis of the stopper and extend right through the knob 2, so that fluid can be discharged in a direction parallel to the axis and without being deflected laterally, as is the case when the channels do not extend through the knob, but are closed at the outer end or are made to extend laterally to the sides of the stopper.

5 is an elastic ring of suitable material—such as india-rubber—inserted within an internal annular groove 6, formed in the bot-

tle-neck. This elastic ring, when the bottle is to contain aerated liquid, need only loosely fit the annular groove 7, formed between the valve 1 of the stopper and the knob 2, and 5 need not fit tightly upon the stem 3.

Such a stopper, when applied to a bottle containing aerated liquid, will be forced upward by the pressure of the gas within the bottle, so that its valve 1 will normally bear 10 against the elastic ring 5, which forms a seat, as shown in Fig. 1, and will thus hermetically close the bottle. If the bottle be inverted and the stopper be pressed inward by any suitable opener—as, for example, by that 15 shown in dotted lines at A in Fig. 2—the valve 1 will be caused to leave its seat, so that the channels 4 will be partly uncovered, as shown, and liquid will flow out through said channels into a glass or tumbler B below, 20 and if the stopper be released the valve will be returned to its seat, thus again closing the bottle until the stopper is again pressed inward.

By making the lower part 1 of the stopper 25 of the conoidal form shown it can be readily passed through the elastic ring to place it in position.

The opener A (shown in Fig. 2) comprises three arms to rest upon a glass, and a central 30 hollow boss to enter the bottle-mouth and press the stopper from its seat.

In Figs. 5 and 6 the elastic ring 5 is made of a thickness corresponding approximately to the width of the groove 7 in the stopper, 35 and its internal diameter is such as to closely fit the connecting-stem 3, which forms the bottom of the groove, as shown. By this construction the ring normally holds the stopper in the closed position and effectually closes 40 the discharge channel or channels therein. The lower end of each channel in this case terminates in the groove 7 at a point 8 a short distance above the lower side of the groove, so that the channel is effectually closed by 45 the ring when the stopper is in its normal position. Such a stopper with elastic ring, while applicable to a bottle containing aerated liquid, is especially applicable to bottles for containing fermented or still liquids, be- 50 cause immediately an external force applied to open the stopper is removed the elastic ring will raise the stopper into a position in which it will close the discharge-channels 4 and effectually seal the bottle. When such 55 a stopper is applied to a bottle containing still liquid and the stopper is opened, liquid will flow out by one of the channels and air will enter the bottle by the other.

The stopper, (shown in Figs. 1 and 2,) instead of being formed with two independent lateral channels 4, may be formed with one channel only; but I consider it better to use two, as they can then be made smaller than when one only is used, and liability of the 60 ring being forced upward from its seat through the one channel when used with bottles containing liquid charged at a high pressure is

obviated. The two lateral channels can be merged into one that may extend through the knob 2 and stem 3 from one side to the other, 70 as shown at 4* in Figs. 7 and 8, or the knob may be formed with one central channel 4* that communicates at its lower end with two lateral channels 4*, that pass through the stems, as shown in Figs. 9 and 10. To prevent the stopper being forced into the body 75 of the bottle during the charging thereof with liquid under very high pressure, the lower part 1 of the stopper can be made of wedge form, as shown in Fig. 12, and the neck of the 80 bottle can be contracted, as shown at 9, Fig. 11, so that should the stopper be unduly pressed inward it will be arrested by the contracted part 9 of the neck and be prevented from being forced from the ring 5. For a 85 like purpose the bottle can be made with an internal annular shoulder 10 surrounding the bottle-mouth, as shown in Fig. 13, and the knob 2 can be enlarged at its upper end, as shown, so that should there be any tendency 90 to force the stopper too far into the bottle the enlarged part of the knob will come into contact with the shoulder and prevent any further inward motion of the stopper.

The operation of the stoppers (shown in 95 Figs. 7 to 13, inclusive) is similar to that hereinbefore described with reference to Figs. 1 to 4.

In Fig. 14 a second ring 11 is shown interposed between the shoulder 10 in the bottle-mouth and the under side of the enlarged part of the knob 2 for the purpose of keeping the stopper raised, and thus insuring a tight joint between the valve 1 and its seat or ring 5. With this construction the annular groove 105 6 is not essential, and the bottle can be formed only with an annular surface or shoulder corresponding to the top side of the groove 6. (Shown in Fig. 14.) This arrangement of stopper and rings, though suitable for bottles 110 containing aerated liquid, is more particularly suitable for bottles containing fermented liquors and still liquids.

In filling bottles fitted with stoppers such as hereinbefore described with liquids under 115 pressure, the filling-machine should be provided with a nozzle adapted to press the stopper inward and hold it in its open position during the filling operation, so that the bottle can be properly sniffed.

What I claim is—

1. A bottle-stopper comprising a lower part forming a valve 1, a knob 2, a connecting-stem 3, a groove 7, formed by and between said knob, valve, and stem, and one or more exit-channels formed partly in said knob and partly in said stem and the lower end of each of which terminates in the said groove at a point below the top side of said groove and a short distance above the bottom side thereof, substantially as herein described, for the purpose specified.

2. The combination, for stoppering a bottle, of a stopper formed with an external annular

groove and with an exit-channel, and an elastic ring arranged partly within the groove in said stopper and partly within an internal groove formed in the bottle-neck, said ring serving to carry said stopper and to normally close said exit-channel, substantially as herein described, for the purpose set forth.

3. The combination, for stoppering a bottle, of a stopper comprising a valve 1, a knob 2, a connecting-stem 3, a groove 7, formed by and between said valve, knob, and stem, and one or more channels formed partly in said knob and partly in said stem, and an elastic ring arranged partly within said groove in the stopper and partly within an internal groove formed in the bottle, said ring forming an elastic seat for the valve 1 of said stopper, substantially as herein described, for the purpose set forth.

20 4. The combination, for stoppering a bottle, of a stopper comprising a valve 1, a knob 2, a connecting-stem 3, a groove 7, formed by and between said valve, knob, and stem, and one or more exit-channels each terminating at a point a short distance above the lower side of said groove, and an elastic ring arranged partly within said groove 7 and partly within an annular groove 6, formed in the bottle and closely fitting said connecting-stem, said elastic ring being of a thickness corresponding, or approximately so, to the width of said groove 7, substantially as herein described, for the purpose specified.

25 5. The combination, for stoppering a bottle, of a stopper comprising a valve, a knob, a connecting-stem, a groove 7, formed by and be-

tween said valve, knob, and stem, and one or more exit-channels formed partly in said knob and partly in said stem, and an elastic ring arranged partly within said groove 7 and partly within an internal groove 6, formed in the bottle-neck, said bottle-neck being contracted or made of less internal diameter at one part than the external diameter of a part of the stopper in proximity thereto, and said contracted or reduced part being so located that said stopper will come in contact therewith when pressed inward before it can entirely leave its elastic ring, substantially as herein described, for the purpose specified.

30 6. The combination, with a bottle formed with an internal groove 6 and with a shoulder 10, of a stopper comprising a valve 1, a knob 2, a stem 3, a groove 7, formed by and between said valve, knob, and stem, and exit-channels 4, and an elastic ring 5, arranged partly within each of said grooves 6 and 7, said knob 2 being formed with an enlarged part adapted to come in contact with said shoulder 10 before said stopper, when forced inward, can leave said elastic ring, substantially as herein described, for the purpose set forth.

In testimony whereof I have signed my name to this specification in the presence of two subscribing witnesses.

WILLIAM PRIESSNITZ BONWICK.
